UNITED STATES PATENT OFFICE.

WILLIAM A. DEMMON, OF KANSAS CITY, MISSOURI.

TRANSFORMATION SCENE.

SPECIFICATION forming part of Letters Patent No. 537,441, dated April 16, 1895.

Application filed August 3, 1894. Serial No. 519,322. (No model.)

To all whom it may concern:

Be it known that I, WILLIAM A. DEMMON, a citizen of the United States, residing at Kansas City, in the county of Jackson and State of Missouri, have invented certain new and useful Improvements in Transformation Scenes, of which the following is a specification, reference being had therein to the accompanying drawings.

My invention relates to improvements in transformation scenes for use in theaters or other places of amusement, and also as a toy or advertising medium.

It consists of the novel arrangement and combination of parts, whereby different characters, landscapes or other paintings near opposite ends of a canvas may be brought into view of the audience by simply manipulating a set of rollers in the manner hereinafter described.

In the drawings which illustrate my invention, Figure 1 represents the character located near the upper end of the canvas. Fig. 2 shows the vertically operating rollers raised to a point about midway between the upper and lower portions of the frame, and represents the character located near the upper end of the canvas disappearing between said rollers while the character located near the lower end of the canvas is making its appearance from the same source. Fig. 3 is a vertical sectional view taken on line 3—3 of Fig. 2. Fig. 4 is a cross sectional view taken on line 4—4 of Fig. 3.

In the construction of my invention I employ a rectangular frame 1, the vertical sides of which are provided upon their inner faces with vertical grooves 2, that extend almost the entire length of said sides. This rectangular frame is reinforced at each corner by means of blocks 3, in which are journaled rollers 4, 5, for the purpose hereinafter described.

6 represents a pair of rollers journaled one above the other in movable blocks 7. Said blocks are provided upon their outer vertical sides with tongues 8, which operate in grooves 2, the same acting as a guide to the blocks when they are moved up or down with the rollers 6.

For convenience in operating blocks 6, I connect them together with a cross-bar 9, which is provided at its upper and lower sides, midway between the movable blocks, with staples 10, to which are secured the opposite ends of a cable 11. 55

12, and 13 represent pulleys located at the upper and lower ends of the rectangular frame, which act as guides for the cable 11, and also keep the lower portion of same within easy reach of the operator upon the floor. 60

14 represents the canvas or other suitable material, upon which are drawn the desired pictures, &c. The upper end of this canvas is secured to the upper cross piece of the rectangular frame. Its free end is then brought 65 down between rollers 6, back up over roller 4, down around roller 5, up between rollers 6, and then down to the lower cross piece of the rectangular frame, to which it is secured. By this arrangement of the rollers and canvas one character is being brought into view from between rollers 6, as fast as the other disappears between said rollers, by simply raising or lowering the same. While I have shown this arranged to be operated from the 70 floor, I do not wish to confine myself to this specific mode of operation, as cable 11, may be run over suitably arranged pulleys, to the flies of the theater, without departing from the spirit and scope of my invention. 75 80

Having thus described my invention, what I claim, and desire to secure by Letters Patent, is—

1. In a transformation scene, the combination with a suitable frame, of rollers journaled at opposite ends thereof, oppositely disposed blocks which are adapted to slide upon the sides of said frame, intermediate rollers which are journaled in the blocks, a canvas having characters depicted thereon one of 85 90 which is being brought to view while another is disappearing, by manipulating the rollers journaled in the blocks, and means for operating said rollers, substantially as set forth.

2. In a transformation scene, the combination of a rectangular frame having vertical grooves in two of its opposite sides, of two rollers which are located at opposite ends of 95

the grooved sides of the frame, a pair of movable blocks provided with tongues which fit into the side grooves, a pair of rollers journaled in said blocks, a canvas or other suitable material, having two characters drawn thereon, one of which is brought into view while the other is disappearing, by manipulating the rollers journaled in the blocks, and

means for operating said rollers, substantially as shown and set forth.

In testimony whereof I affix my signature in presence of two witnesses.

WILLIAM A. DEMMON.
